HERMAN L. HARTZELL, OF ANDERSON, INDIANA, ASSIGNOR TO DELCO-REMY CORPORATION, OF ANDERSON, INDIANA, A CORPORATION OF DELAWARE

IGNITION COIL

Application filed May 23, 1930. Serial No. 455,084.

This invention relates to improvements in ignition coils.

It is among the objects of the present invention to provide an ignition coil of simple structure and design, capable of being produced commercially at a minimum cost.

Another object of the present invention is to secure the cover cap to the casing of the ignition coil in a simplified manner.

Further objects and advantages of the present invention will be apparent from the following description, reference being had to the accompanying drawings, wherein a preferred embodiment of one form of the present invention is clearly shown.

In the drawings:

Fig. 1 illustrates the ignition coil in side elevation.

Fig. 2 is a plan view of the ignition coil.

Fig. 3 is a fragmentary sectional view taken along the line 3-3 of Fig. 2.

Fig. 4 is an inverted plan view of the cover cap with a section of the casing or can attached.

Fig. 5 is a sectional view taken along the line 5-5 of Fig. 4.

Referring to the drawings, the ignition coil comprises a can or cylindrical casing 20, having a bottom 21. Within this can are contained the elements of the ignition coil which comprise a core 22 surrounded by the secondary winding 23. The primary winding 24 surrounds the secondary winding 23 and about the primary winding there is provided a magnetic body 25 which fits tightly into the can or casing 20. Two lead wires 26 and 27 are connected with the primary winding 24.

A cover cap 28 is provided for the can 20, said cover cap being made of suitable insulating material, such as bakelite. This cover cap has an interior, central cylindrical extension 29 into which one end of the core 22 fits and is supported thereby. A central, tubular extension 30 has the terminal 31 therein, said terminal being in electrical connection with the core 22 through the spike 32, the head of which engages the terminal 31, said spike being driven between the lamination forming the core 22. One end of the high tension or secondary winding 23 is con-

nected with the core 22 in any suitable manner.

The cover cap 28 has a cylindrical portion 33 substantially concentric with portion 29 and which fits into the casing or can 20, said cylindrical portion 33 having an annular groove 34 formed therein. An annular flange 35 is provided on the cover cap, said annular flange having a recess 36 provided therein, one side wall of said recess being substantially flush with the outer surface of the cylindrical portion 33 of the cover cap 28. When the cover cap 28 is placed upon the can 20, the end of the can extends into the annular recess 36. After the cover cap and can are so assembled, the annular portion of the can 20, designated by the numeral 40, is pressed into the annular groove 34, as shown particularly in Fig. 5, whereby the cover cap and can are securely fastened together.

The cover cap has two diametrically opposed lug portions 41 and 42, forming increased areas in the cover cap. Within the lug portion 41 there is provided a terminal stud 43, while a similar terminal stud 44 is provided in the lug portion 42. The wire 26 leading from one side of the primary winding 24 is in electrical engagement with the terminal stud 43, and the wire 27 of the other end of the primary winding 24 is in electrical connection with the terminal stud 44. Diametrically opposite radial ribs 45 and 46 are provided in the cover cap 28 between the central cylindrical portion 29 and the outer cylindrical portion 33 thereof, said annular ribs 45 together with the lugs 41 and 42 providing reinforcing members in the cover cap 28 which substantially prevent crushing of said cover cap when the pressing force is applied to force the annular portion 40 of the casing or can 20 into the annular groove 34.

Terminal stud 43 has a terminal clip 50 secured thereto by nut 51, while a similar clip 52 is secured to terminal stud 44 by the nut 53.

From the foregoing it will be seen that applicant has provided an ignition coil in which the cover cap is attached to the casing in a simplified and inexpensive manner, the method of attaching these two elements com-

prising a joint which hermetically seals the ignition coil.

While the form of embodiment of the present invention as herein disclosed, constitutes a preferred form, it is to be understood that other forms might be adopted, all coming within the scope of the claims which follow.

What is claimed is as follows:

1. In a device of the character described, the combination with an insulating body having a cylindrical portion provided with an annular groove in its outer surface; an annular flange on said body provided with an annular recess; and a cylindrical metal case fitting about the cylindrical portion of the insulating body and into the recess in its flange, an annular portion of said case being pressed into said annular groove to secure the insulating body to the case.
2. In an ignition coil the combination with a metallic casing containing the primary and secondary windings of the ignition coil; of an insulating body having an annular flange provided with an annular recess for receiving the end of the casing; a cylindrical portion fitting into said casing, said portion having an annular groove into which an annular portion of the case is pressed to secure the insulating body and casing together; two diametrically opposite lugs in the insulating body; a terminal in each lug for receiving the ends of the primary winding respectively; radial ribs in the insulating body, said lugs and ribs reinforcing the insulating body to withstand the pressure for forcing the casing into the annular groove of said body.

In testimony whereof I hereto affix my signature.

HERMAN L. HARTZELL.
